UNITED STATES PATENT OFFICE.

LOUIS SUEDMEYER, OF ST. LOUIS, MISSOURI.

TOBACCO-PIPE.

1,336,393.

Specification of Letters Patent.

Patented Apr. 6, 1920.

Application filed October 18, 1918. Serial No. 258,697.

To all whom it may concern:

Be it known that I, LOUIS SUEDMEYER, a citizen of the United States, residing in the city of St. Louis and State of Missouri, have 5 invented new and useful Improvements in Tobacco-Pipes, of which the following is a specification.

This invention relates to pipes, and has 10 for its object to provide a pipe in which the products of condensation from the tobacco will be removed during smoking and can be readily discharged at any time by the smoker; which will thoroughly filter 15 and cleanse the smoke after the removal of the products of condensation; which will protect the pipe material and stem from becoming saturated with the liquid distilled out of the tobacco during smoking; and which may be readily adapted to a new 20 bowl and stem without the necessity of procuring a new bit and cleaner.

In the drawings herewith I have illustrated one embodiment of my invention, but it will be understood that this illustration 25 as well as the descriptive portion of this specification are in no sense restrictive of the invention, as it may be varied within the range of mechanical skill without departing therefrom.

30 In said drawings:—

Figure 1 is a longitudinal sectional view vertically of a pipe made in accordance with my invention.

Fig. 2 is a view in plan, partly in section.

35 Fig. 3 is a transverse section on substantially the line 3—3 of Fig. 1 to illustrate the construction of one of the cleaner pockets.

Fig. 4 is a longitudinal sectional view vertically showing a slightly different adap- 40 tation of the invention.

Fig. 5 is a longitudinal section of the cleaning device proper, showing a further adaptation of the invention.

Fig. 6 is a transverse section on substan- 45 tially the line 6—6 of Fig. 1.

Fig. 7 is an end view of a bit peculiarly adapted to be used with my invention.

Fig. 8 is a transverse section through the structure shown in Fig. 5.

50 Fig. 9 is a view in section illustrating a slightly different disposition of the purifying device in the stem of the pipe.

Fig. 10 is a sectional view showing the application of the invention to a curved 55 stemmed pipe.

Referring to the drawings by numbers,

like numbers indicating like parts in the several views, 10 indicates a pipe bowl of any desired shape or material, the form here shown as the ordinary briar pipe. The 60 stem 11 projects from the bowl in the usual manner, a straight stem being here shown extending at right angles from the pipe, although it will be understood that the stem may extend at other angles to the pipe and 65 be still adapted to the use of my invention. The stem is finished with the usual ferrule 12, if desired.

The stem 11 is provided with the smoke 70 passage 13 from the bowl, this smoke passage extending through a relatively thin partition or wall 14 between the bowl and the main bore of the stem. The bore 15 of the stem is somewhat larger than is customary and extends from the wall 14 to the 75 rear of the stem so as to furnish a relatively large passage lengthwise of the stem.

Within this bore 15 of the stem 11 is the smoke purifying device proper which comprises a member 16, preferably cylindrical 80 in cross section and made of any suitable material impervious to moisture, for example, metal, a light alumina alloy being a good material from which to construct the member 16. The purifying member 16 has 85

in its forward end wall, and preferably above the horizontal center thereof, a draft hole 17, which coincides with the smoke 90 passage 13 in the wall 14, the end wall of the smoke purifying member 16 fitting snugly against the wall 14 when the member 16 is in the bore of the pipe. The draft hole 17 leads to a well or pocket 18, preferably of cylindrical form, in the member 16, this pocket being open at its top and having 95 its side walls slightly inclined and bottom wall curved into the side walls so as to eliminate crevices or interstices so far as possible.

The pocket 18 communicates by a tangentially-placed passage 19 with a second 100 pocket 18 of similar form, and said second pocket by a tangential passage 19 disposed on the opposite side of the second pocket and out of line with the first-named passage 19 communicates with a third pocket of 105 similar form as those described. From the third pocket 18 a draft passage 20 leads to a chamber 21 in the rear of the member 16, the passage 20 being preferably barred or screened by the bars 22.

It is obvious that the number of pockets 18 may be increased or diminished as de-

sired without departing from the spirit of the invention, as the number of pockets used will depend on the style of pipe, the length of stem, and the needs of the particular 5 user.

The action of the purifying member as thus far described will be to lead the smoke through the draft passage 17 into the cylindrical pocket 18 in which the smoke, due 10 to the curved wall of the passage, will be given a whirling motion, which will throw down by centrifugal action the impurities or heavy content of the smoke, and at the same time, by reason of its increased length 15 of travel, cool it before it passes, under draft, through the passage 19 leading to the second pocket. The passages 19 being staggered or out of line with one another, this same gyrating movement of the smoke, 20 throwing down of the heavy content, and cooling of the smoke will occur in each of the pockets, and the inclination rearwardly of the walls of the pockets will, of course, tend to carry the purified smoke upwardly 25 as it passes from pocket to pocket toward the passages 19, which are cut in the upper edges of the pocket separating web.

The smoke thus cooled and purified of the heavier products thrown down into the 30 pocket passes by the draft passage 20 to the chamber 21, which chamber is of sufficient capacity to receive a filtering medium, such as cotton or other suitable material 23, and this filtering material will be packed in in 35 a loose manner so as not to check or interfere with the draft through the pipe, the bars 22 preventing the material from entering the draft passage 20 and clogging. The chamber 21 will be closed at its rear end by 40 any suitable bit 24, the said chamber being tapered so as to give the usual wedging fit between the bit and chamber, and preferably the bit will be provided across its draft passage with a suitable screen or bar 25 to 45 prevent the filtering material 23 from being sucked into the draft passage of the bit.

The member 16 is preferably tapered at its rear end, as at 26, to give the usual wedging fit in the bore of the stem 11, although 50 it will be understood that any other connection desired can be adopted other than the tapering wedging connection shown. The tapered portion of the member 16 not only gives the proper wedging action to secure 55 the parts together, but it projects rearwardly from the stem of the pipe so that it may be readily grasped to withdraw the purifier without soiling the fingers and without the necessity of putting any undue 60 breaking strain on the bit. While I have described the member 16 as having its rear end tapered, it will be understood that the taper may, if desired, extend the entire length of the purifying device so as to give 65 a good wedging fit in the bore of the pipe.

Preferably the member 16 and the stem will be provided with registering marks, as 27, which will indicate to the user that the member 16 is in proper position, namely, with the mouths of the pockets 18 opening 70 upwardly, and danger of inserting the smoke purifying member in such manner as to permit the extracted contents of the pockets escaping in the bore of the stem by reason of the member 16 being in inverted 75 position is eliminated.

It will be seen that in the construction described, the smoke will be completely purified, cooled and filtered before reaching the mouth of the user, and the fluids and products of condensation in the smoke will be kept from contact with the material of the pipe and stem, and danger of saturation and fouling of the pipe and stem until they become disagreeably "strong" is eliminated. 80 It will be seen that none of the collected impurities can run forward into the bowl of the pipe for they are effectively trapped in the pockets and cannot escape therefrom by way of the draft passages either forwardly into the bowl of the pipe or rearwardly into the mouth of the smoker. Furthermore, the construction is such as to admit of ready cleaning of the smoke-purifying member 16 for the user can at any time 85 withdraw the member 16 and throw the contents of the pockets out, and he can also very readily remove the bit and the filtering material can be withdrawn from the chamber 21 and renewed. The cylindrical 100 shape of the pockets 18 lends itself to the ready cleaning of the member, for there are no corners or interstices in which the products of condensation thrown down can accumulate, the walls of the pockets 18 being 105 smooth, and the bottoms being rounded, as shown, so as to present practically no places for lodgment of foreign matter. After continued use, and when it is desirable to completely freshen up the member 16, it may be 110 removed and subjected to any cleaning desired, for example, heating or boiling to very completely cleanse it of any deposits.

In that form of the invention shown in Fig. 5, I have illustrated the smoke-purifying member as being provided with a projection 36 at its forward end designed to register with the draft passage 13 in the wall 14 between the bowl and the bore of the stem. This projection 36 has the function of keeping the draft passage 13 clear of any deposits, and, furthermore, prevents burning or charring of this passage without unduly heating the member 16 by conduction, for it will be understood that the partition 14 between the bowl and the bore 15 of the stem 11 is for the purpose of insulating the cooling member 16 from the bowl, so that the said member will not become over-heated from the bowl contents. Where 130

the projection 36 is off-center, as here shown, it will serve also as a registering means to insure the member 16 always being inserted in the bore 15 of the stem in such position 5 as to maintain the pockets 18 in a vertical position within the stem.

In order to prevent any contact of the smoke or thrown-down products of the smoke with the material of the stem and a 10 resulting saturation of that material, the member 16 may be provided, if desired, with a thin shell 28, as shown in Fig. 4, which shell will have a retaining rim 29 at its rear end, so that it may be withdrawn when 15 the member 16 is taken out for cleaning, and slipped off such member to permit the contents of the pockets to be thrown out.

A variation of this shell 28 is illustrated in Figs. 5 and 8, in which a cover plate 30 20 is provided of sufficient area to cover the pockets 18, as shown.

It will be observed that in that form of the invention disclosed in Fig. 9 the purifier 31 is differently disposed with respect to 25 the pipe bowl, the orifice in the front wall of the purifier being dispensed with and the bore 32 in the stem being extended forwardly beneath the bowl pocket 33, so as to bring the first cell or pocket of the purifier 30 directly beneath the draft passage 34 35 in the bottom of the bowl. This results in the first pocket or cell forming a receiving chamber for any drainage or products of condensation in the bowl so that the bowl will be properly freed of any liquid products which collect in the bottom and they 40 may be readily removed and thrown out of the purifier.

In Fig. 10 the device is shown as applied 45 to a pipe 10 having a curved stem having the usual ferrule 12 as in the other forms. The purifier 16, which is tapered throughout its length in order to snugly fit the bore of the stem, has the closed end wall similar 50 to the form shown in Fig. 9, and the smoke passage 35 is arranged at an incline, as shown, so as to deliver to the first pocket 18, the pockets being connected as in the other forms by the offset passages 19, the rear wall having the opening 20 forming a 55 smoke passage to the filtering chamber at the rear end of the purifier, which filtering chamber receives also the end of the bit.

It will be observed from the foregoing 60 that a pipe is provided in which the smoke will be thoroughly cleansed and cooled before reaching the mouth of the smoker; in which the products eliminated by the cleansing process may be quickly and without difficulty thrown from the pipe and this 65 may be done while the pipe is in use and without the necessity of throwing out the tobacco charge and interrupting the smoking to an appreciable extent for purposes of cleansing. Furthermore, the device may

be very cheaply constructed, and as has been heretofore stated, may be fitted to a new bowl or stem without the necessity of renewing it or the bit.

I claim:

1. The combination in a pipe having a bowl and a solid bored stem with a connecting draft passage between them, of a purifier insertible endwise in said stem, having a plurality of open-topped, circular smoke-whirling pockets, to one of which said draft passage delivers, and off-centered alternately-staggered passages connecting said pockets. 70

2. The combination in a pipe having a bowl and a solid bored stem with the stem bore extending beneath the bowl and connected therewith by a draft passage, of a purifier insertible endwise in said stem and having a plurality of open-topped, circular, 85 smoke-whirling pockets, the forward one of which is in communication with said passage, and off-centered, alternately-staggered passages connecting said pockets. 80

3. The combination, in a pipe having a bowl and solid bored stem; of a purifier insertible endwise in said stem and having a draft passage in its front and rear ends, a plurality of open-topped, circular, smoke-whirling pockets connecting said front and 90 rear passages, and off-centered alternately-staggered passages connecting said pockets. 95

4. The combination, in a pipe having a bowl and solid bored stem; of a purifier insertible endwise in said stem and having a draft passage in its front and rear ends, a plurality of open-topped, circular, smoke-whirling pockets intermediate its ends and in communication with one another and with said passages; and a removable closure 100 for said pockets. 105

5. The combination, in a pipe having a bowl and solid bored stem; of a purifier insertible endwise in said stem and having a draft passage in its front and rear ends, a plurality of open-topped, circular, smoke-whirling pockets intermediate its ends and in communication with one another and with said passages; and a removable pocket-closing shell fitted to said purifier. 110 115

6. The combination, in a pipe having a bowl and solid bored stem; of a purifier insertible endwise in said stem and having a draft passage in its front and rear ends, a plurality of open-topped, circular, smoke-whirling pockets connected by tangentially-disposed staggered passages communicating with said smoke passages, and a filter- and bit-receiving chamber at the rear end of said purifier. 120

7. The combination, in a pipe having a bowl and solid bored stem; of a purifier insertible endwise in said stem and having a perforated projection at its front end to form a passage, a filter- and bit-receiving 125 130

chamber at its rear end having a draft-passage, and a plurality of open-topped, circular, smoke-whirling pockets communicating with said passages and connected by 5 tangentially-disposed, alternately staggered passages.

8. The combination, in a pipe having a bowl and solid bored stem; of a purifier insertible endwise in said stem and having an 10 eccentrically-placed perforated projection at its front end to form a passage and center the purifier, a filter- and bit-receiving chamber at its rear end having a draft-passage, and a plurality of open-topped, 15 circular, smoke-whirling pockets communicating with said passages and connected by tangentially-disposed, alternately staggered passages.

9. The combination, in a pipe, of a bowl, 20 a solid stem having a relatively large bore, a perforated wall between said bowl cavity and said bore, a purifier insertible endwise in said bore and having a perforated front end to engage said wall, an externally- 25 tapered filter- and bit-receiving chamber at the rear end of said purifier to make wedging engagement with said bore having a draft-passage therein, and a series of interconnected smoke-whirling pockets between 30 said ends in communication with said draft-passages.

10. A smoke-purifier for pipes, comprising 35 a stem-engaging plug having a perforated front end; a perforated rear end; and a plurality of open-topped, circular

pockets connected by tangentially-disposed, alternately-staggered passages between said ends; the end pockets of the series connecting, respectively, with the perforated front and rear ends of the plug.

11. A smoke-purifier for pipes, comprising 40 a stem-engaging plug having a body-portion, which is tapered for wedging engagement with the bore of the stem and provided with a filter- and bit-receiving chamber, a front wall having a draft-passage, a wall at the forward end of said filter chamber having a draft-passage, and an open-topped, circular, smoke-whirling pocket communicating with said passages.

12. A smoke-purifier for pipes, comprising 45 a single-piece, stem-engaging plug having a cylindrical body-portion, the front and rear walls of which are provided with draft-passages, said plug having a tapered hollow filter- and bit-receiving chamber at the rear end of said body-portion; and a plurality of open-topped, circular, inclined pockets having concave bottoms in said body-portion and connected by tangentially- 50 disposed, alternately-staggered passages; the end pockets of the series communicating, respectively, with said draft-passages.

In testimony whereof I have hereunto set 55 my hand in presence of two subscribing witnesses.

LOUIS SUEDMEYER.
